UNITED STATES PATENT OFFICE.

MAHLON E. LAYNE, OF HOUSTON, TEXAS, ASSIGNOR TO LAYNE & BOWLER CORPORATION, OF LOS ANGELES, CALIFORNIA, A CORPORATION OF CALIFORNIA.

CENTRIFUGAL PUMP.

Application filed February 24, 1926. Serial No. 90,252.

This invention relates to rotary and centrifugal pumps of the type employed in deep water wells and the like. Rotary pump mechanisms of the type to which this invention relates generally comprise a pump proper which is suspended in a well hole and connected by shafting to the top of the well and there driven either by a pulley or electric motor axially aligned with the pump shaft 10 of the pumping mechanism. Due to the varying depths at which the pump proper is suspended in the well, such pump mechanism requires a provision for the adjustment of this pump shaft after the mechanism is installed 15 in order that the impellers of the pump may be properly centered in the pump bowl. Accordingly, the art has for some time employed a separate bearing for supporting the pump shaft through which the pump shaft may be 20 longitudinally adjusted, and a flexible coupling for coupling the pump shaft to an electric motor axially aligned with the pump shaft when the rotary pump mechanism is to be directly driven by an electric motor in 25 place of a pulley. Such additional bearings and flexible couplings add complications of expense to the cost of the rotary pump mechanism which could be avoided if suitable means could be provided for coupling the motor shaft and the pump shaft together in 30 such a way as to permit adjustment of the impellers of the pump shaft to center the same in the pump bowl.

It is an object of the present invention to 35 provide a rotary pump mechanism in which this adjustment of the impellers of the pump bowl is accomplished with the pump shaft and motor shaft rigidly connected together so as to act in operation as a single integral 40 shaft.

Various further objects and advantages of the invention will be apparent from a description of a preferred form of centrifugal well pump embodying the invention, for which 45 purpose reference is made to the accompanying drawings, in which the invention is illustrated in its preferred form.

In the drawings:

Fig. 1 is an elevation, partly in vertical 50 section, of the rotary pump mechanism embodying this invention.

Fig. 2 is an enlarged elevation, partly in vertical section of the shaft coupling means.

In the drawings, the rotary well pumping 55 mechanism is indicated as in position in a

well hole provided with a well casing 2. 3 indicates the pump proper connected at its lower end to an inlet pipe 4. The pump proper includes one or more impellers 5 connected to a vertical pump shaft 6 which extends from the pump to above the top of the well. The pump proper 3 connects with the discharge casing 7 concentrically with the pump shaft 6, which discharge casing 7 likewise extends to the top of the well and serves to support 60 or suspend the pump in the well. The pump shaft 6 is enclosed from contact with the water pumped by the shaft enclosing casing 8 indicated as built in sections coupled together by bearing blocks 9, which shaft 8 likewise 65 extends to the top of the well.

At the top of the well the discharge casing 7 is connected to a casing head 10 having the usual lateral discharge elbow 11, said casing resting upon a foundation 12. On the top 75 of the casing head 10 is mounted a motor stand 12^a which supports the stator 13 of an electric motor which may be of any preferred or customary construction in so far as details of electrical factors are concerned, said motor being indicated in this example of the invention as an induction motor with the usual laminated core 14, mounted upon a motor shaft 15 which is vertically disposed and aligned with the pump shaft 6.

The top of the stator 13 of the motor mounts a bracket or cover 16 which provides a support for radial and thrust bearings 17 illustrated as preferably of the ball type, which thrust bearings support through a 90 collar 18 the motor shaft 15 and thereby the core 14 of the motor upon the bracket 16, the weight hence being distributed through the casing head 10 to the foundation 12. The bracket is shown as threaded to a sleeve 19 95 extending up close to and around the motor shaft 15 to provide a means for retaining oil around the bearings 17.

In order that such pump shaft 6 and motor shaft 15 may be rigidly connected together 100 to act in operation as one integral shaft while still permitting of such assembling of the mechanism that the impellers 15 carried by the pump shaft 6 are properly centered in the pump holes, the discharge casing head 10 is made of novel construction and the shafts 6 and 15 are coupled in a novel manner. The shafts 15 and 6 are indicated as both threaded to a coupling 20 with the ends of the shafts spaced slightly apart. The coupling 110

20 is provided with a wrench engaging nut 21 and the pump shaft 6 is provided with a bore 22 aligned with the axis of the pump shaft and with the threaded bore 23 at the 5 end of the motor shaft 15. Threaded into such bore 23 is a dentil 24 of a size to fit tightly the recess 23 in the shaft 15, and the recess 22 in the shaft 6. When these shafts are brought together in that position which 10 centers the impellers 5 in the pump 3, said dentil 24 operates to maintain such shafts 15 and 6 in axial alignment and prevents weaving of such shafts, which would take place were such shafts coupled together without 15 their ends tightly abutting if no dentil such as 24 was employed.

The use of such means in connecting the pump shaft 6 and motor shaft 15 provides a simple means by which these shafts may be 20 correctly rigidly attached together at the time the rotary pump mechanism is installed, inasmuch as dentils 24 of various different lengths may be provided with an apparatus, or such dentils may be cut into the correct 25 length at the time of the installation of the apparatus, thus providing a simple and inexpensive means by which the shafting may be made rigid with proper allowance for the centering of the impellers 15.

30 In order that such connection may be made, the casing head 10 is shown as constructed in two parts, of which 25 is the upper part and 26 the lower part, the parts 25 and 26 having interlocking faces 27 so that they will always 35 be assembled in a predetermined position, and are clamped together by suitable means such as indicated at 28.

The lower part 27 of the casing head 10 is indicated as forming merely a bottom for the 40 casing head 10 and provides a neck 29 threaded to the discharge casing 7. The upper part 25 of the discharge casing head 10 is provided with a depending neck 30 extending axially downward through the casing head and is threaded at its lower end 31 to the upper end of the shaft enclosing casing 8, said shaft enclosing casing 8 being indicated as provided with an arm 32 engaging an abutment 33 on the discharge casing 7 to 45 prevent rotation of these parts relative one to the other. The neck 30 at its upper end supports a bearing sleeve 34 for the motor shaft 15, this bearing sleeve thus being disposed within the casing head and in position 50 to be cooled by the water pumped, no other radial bearing being necessary below the rotor 14 of the motor; and between such sleeve 34 and the lower end of the neck 30, the neck is provided with an enlarged bore 55 35 enclosing the coupling 20, and said neck is there joined with a wrench admitting and supporting web 36 extending radially to the outer side of the discharge head 10 and normally closed by a plug 37.

60 -65 With a rotary pump mechanism thus con-

structed, all of the load of the pump shaft impellers, rotor and motor shaft may be supported upon the same bearings 17, these being mounted above the rotor of the driving member 14 to suspend such parts in a plumb-bob 70 fashion, which has a marked tendency to lessen or eliminate weaving of the mechanism. The use of additional bearings and flexible couplings between the motor and discharge head is avoided, the motor shaft 75 15 of the pump shaft 6 are in use one integral shaft, although their ends may be various distances spaced apart, and this construction permits of a ready assembly of the mechanism as a whole. 80

While the embodiment of the invention herein described is well suited for accomplishing the purposes and objects of this invention, it is to be understood that various modifications in the details of construction 85 and arrangement of parts may be made without departing from the spirit of the invention, and the invention includes all such modifications and substitutions as come within the scope of the appended claims. 90

I claim:—

1. A rotary pumping mechanism comprising a rotary pump having a vertical pump shaft and a vertical discharge casing, a discharge head connected to the discharge casing, an electric motor supported over the discharge head and having a motor shaft axially aligned with the pump shaft and coupled thereto with the ends of the motor shaft and pump shaft spaced slightly apart, the discharge head having a depending neck enclosing the coupling between said shafts, and a tool supporting tube opening and extending from the neck at a point opposite the coupling between the shafts to the side of 105 the head.

2. A rotary pumping mechanism comprising, a rotary pump having a vertical pump shaft and a vertical discharge casing, a discharge head connected with the discharge casing, an electric motor supported over the discharge head and having a motor shaft axially aligned with the pump shaft and extending into the discharge head, and a coupling within the discharge head coupling said motor shaft 110 to said pump shaft, the discharge head having a depending neck enclosing the lower end of the motor shaft and the coupling between the motor shaft and pump shaft, the discharge head further having a horizontally 115 disposed tube connecting said depending neck with the side wall of the discharge head at a point opposite the coupling between the pump shaft and motor shaft so as to give access to said coupling, whereby to provide 120 a tool supporting tube.

Signed at Los Angeles, Calif., this 17 day of February, 1926.
